UNITED STATES PATENT OFFICE.

SIMON W. WARDWELL, OF PROVIDENCE, RHODE ISLAND.

BRAIDING-MACHINE.

1,008,504.

Specification of Letters Patent.

Patented Nov. 14, 1911.

Application filed May 25, 1910. Serial No. 563,378.

To all whom it may concern:

Be it known that I, SIMON W. WARDWELL, a citizen of the United States, residing at Providence, in the county of Providence and 5 State of Rhode Island, have invented certain new and useful Improvements in Braiding-Machines, of which the following is a specification.

My invention relates to braiding machines 10 and consists of improvements in the stopping-mechanism therefor.

The object of my improvement is to provide a stopping device which will operate first to disconnect the driving means and 15 afterward to apply a braking force to overcome the momentum of the moving parts.

An important feature of my improvement is the method of operation of the brake-ring which provides that when the latter is 20 thrown into engagement with the rotating turret of the machine it is forced thereby against wedges which carry it more firmly against the turret to effect a cumulative braking action.

25 My invention is fully described in the following specification, illustrated by the accompanying drawings, in which:

Figure 1 is a side elevation of a braiding machine, part sectional through the axis to 30 show the operating parts, and illustrating my improved clutch and brake mechanism applied thereto; Fig. 2, an enlarged plan view of the brake and clutch mechanism with the latter shown in section on the line 35 A—A of Fig. 1; Fig. 3, an enlarged detail view of the detent latch, viewed from below; Fig. 4, an enlarged side elevation of the clutch mechanism; Fig. 5, an enlarged detail view of the detent elements for the 40 clutch mechanism, looking in the direction indicated by the arrow f, Fig. 2; Fig. 6, an enlarged elevation of a portion of the brake-ring and its operating devices; Fig. 7, an enlarged plan view of one of the upper carriers 45 showing the tension and let-off mechanism for the yarn; Fig. 8, a side elevation of the same; Fig. 9, a plan view of the lower carrier and supply controlling devices.

The main braiding machine shown and 50 described herein is similar in general to that disclosed in my pending application, Serial No. 537,742, filed January 12th, 1910, and the stopping-mechanism is similar in some respects to that described in my previous 55 pending application, Serial No. 493,718, filed

May 3rd, 1909. Several important improvements have been made in the means for controlling the clutch mechanism and the structure and operation of the brake-ring and these are specifically pointed out here- 60 inafter.

Referring to Fig. 1, the machine consists essentially of the main frame or standard 2 in which are circular ball races 3 and 4 provided with the balls 5 and 6 adapted to 65 roll therein. Mounted on these ball bearings are two turrets 7 and 8 which drive the upper and lower series of carriers 9 and 10, respectively, on which the yarn supplies 11 and 12 are mounted. The lower carriers 10 consist of brackets, illustrated in detail in Fig. 9, and having suitable tension and let-off devices more fully described herein- 70 after, attached rigidly to a flange 13 of the outer turret 8. The turret 8 is also formed 75 with a circular groove 14 in its outer rim which serves as a race-way for the runners 15 of the upper carriers 9. The carriers 9 have decks of rectangular contour, as shown particularly in Figs. 6 and 7 and carry 80 tension and let-off levers for the yarn supplies 11.

The inner turret 7 carries a dish-shaped head 16 on which are mounted drivers 17 adapted to engage the carriers 9 to propel 85 them in the race-way 14. The two turrets are rotated in opposite directions by a bevel gear 18 mounted on the driving shaft 19 and engaging the gears 20 and 21 of the turrets. The under side 146 of the head 16 90 bears against the upper face of the gear 21 on the turret 8 to take the upward thrust of the gear 18 and also the thrust of the brake-ring hereinafter described. The shaft 19 turns in bearings in the overhanging extension 22 of the frame 2 and is driven by suitable means, such, for instance, as the belt pulley 23 adapted to be engaged with the shaft through a clutch member 24, see Fig. 2. The yarns x and y lead up from 100 the lower and upper supplies 12 and 11, respectively, to the braiding point z, and the lower yarns x play in slots in the rim of the turret 8 so as to allow them to pass over and under the upper supplies 11. The yarn supplies 105 revolve in opposite directions and the braiding operation is effected by means of switches 25, mounted on a member 26 which rotates with the turret 7. The switches 25 operate to alternately close and open the 110

openings between the carriers 9 and their driving head 16 and are actuated by a switch-ring 27 oscillated by an arm 28 which is moved by either one of the interchangeable cams 29 and 30, all as fully described in my pending application first referred to above. The drivers 17 are reciprocated in and out of engagement with their carriers 9 to allow the passage of the lower yarns α 10 under the supplies 11 by means of rolls or studs 31 engaging a cam groove 32 in the rim of turret 8.

The driving-pulley 23 is preferably adapted to rotate freely on the shaft 19 when the machine is at rest, and is engaged with the shaft to drive the machine by a novel arrangement of clutch mechanism now described: A clutch-member 24 is secured at the outer end of the shaft 19 by a stud 33 extending through its hub and a transverse hole in the shaft. The clutch-member 24 has a tapered face 34 adapted to engage the corresponding internal face 35 of the pulley 23 which slides longitudinally of the shaft 19 to carry it in and out of engagement. Connected with the hub of the pulley 23 is a sliding sleeve 36 through which the pulley is operated. The sleeve 36 is formed with a flange 37 at its outer end, and secured to the hub of the pulley 23 is a flanged ring 38 which overhangs the flange 37 to provide for connecting the sleeve and pulley to slide together while allowing the latter to turn independently of the sleeve. The end of the bearing 22 is formed with an annular enlargement or rim 39 having a counterbore 40. The sleeve 36 projects into the counterbore 40 and a washer 41 is interposed between its end and the end of the bearing 22. The sleeve 36 also has a counterbore 42 adapted to receive a coiled spring 43 which bears on the washer 41 and tends to force the sleeve 36 away from the bearing 22 to carry the pulley 23 into engagement with the clutch-member 24.

The sleeve 36 has a second flange 44 midway of its ends, and between the latter and the ring 38 is a yoke 45 formed with abutments 46, see Figs. 2 and 4, adapted to bear on the flange 44 to move the sleeve to withdraw the pulley 23 from engagement with its clutch-member 24. Preferably, the yoke 45 completely surrounds the sleeve and is formed with a projecting lug 47 which bears on the rim 39 of the bearing 22 to guide it in its movement. On its opposite side is an arm 48 extending alongside the bearing 22 and having a guiding slot 49, see Fig. 4, through which a pin 50 projects from the bearing 22. The end of the arm 48 is connected by a pin 51 to the short arm 52 of the controlling lever or handle 53, the latter being fulcrumed on a stud 54 extending up from the boss 55 which projects from the frame of the machine. A second lever 56

is also pivoted on the stud 54 above the lever 53 and is formed with two arms 57 and 58. At the end of the arm 57 is pivoted a detent latch 59 having a slight shoulder 60 adapted to engage the shoulder 61 on the pin 62. The latch 59 is held in engagement with the pin 62 by a spring 63 anchored to a lug 64 on the lever 56. A spring 65 connects the end of the arm 58 of the lever 56 to the pin 50 and tends to move said lever in the direction indicated by the arrow a , Fig. 2. The spring 65 has a greater tension than that of the spring 43 which bears on the sleeve 36, and therefore normally acts to move the lever 56 and yoke 45 to slide the sleeve 36 and withdraw the pulley 23 from engagement with the clutch-member 24.

The manually moved controlling lever 53 is connected to operate the lever 56 by means of a pin 67 extending up from a boss on the arm 69 of said lever 53 and projecting through a hole 70 in the arm 57. A clearance for the pin 67 is provided in the hole 70 so that the lever 53 can be moved a slight distance without moving the lever 56. The pin 67 is also adapted to engage a lug 71 projecting from the hub of the latch 59. When the lever 53 is moved manually in the direction indicated by the arrow a , Fig. 2, the pin 67 first engages the lug 71 and rocks the latch 59 to free its shoulder 60 from the pin 62. As soon as the latch 59 is free from its detent the spring 65 acts to move the lever 56 to shift the clutch mechanism and disconnect the driving-pulley from the driving shaft as previously described.

To connect the pulley 23 with its clutch-member 24 to start the operation of the machine the lever 53 is moved in the direction opposite to that indicated by the arrow a . This movement carries the pin 67 away from the lug 71 and against the opposite side of the hole 70 to move the lever 56 in the direction indicated by the arrow b . The yoke 45 connected to the arm 52 of the lever 56 is thereby moved in the direction indicated by the arrow c to release the sleeve 36 and allow the spring 43 to carry the pulley 23 into engagement with its clutch-member 24.

Referring to Figs. 3 and 5, the former being a bottom view of the latch 59, it will be noted that the under side of the end of the latch is cut away at 73 so that the shoulder 61 which engages the pin 62 is of a very slight depth. When this shoulder is released from the shoulder 61 on the pin 62 the surface 73 rests on the side of the pin and the top portion 74 of the latch rides over the top of the pin. This provides that only a slight movement of the latch is necessary to release it to allow the lever 56 to move under action of its spring 65. The beveled

end of the upper portion 74 of the latch is for another purpose hereinafter described. As the lever 53 is moved to cause the engagement of the pulley with its clutch, in the manner above described, the movement of the arm 57 in the direction indicated by the arrow *b* carries the latch 59 into position for its shoulder 60 to engage the pin 62 and the action of the spring 63 effects this engagement. The lever 56 is thus locked by the latch 59 to maintain the yoke 45 in such position as to allow the spring 43 to hold the driving-pulley in operative connection with its clutch member. It will be seen that when the lever 56 is moved far enough to lock the detent latch, the yoke 45 will have been moved in the direction indicated by the arrow *c* a sufficient extent to carry its abutments 46 clear of the flange 44. The sleeve 36 is then free to rotate without contact with the yoke, and turns with the pulley 23 on account of its engagement with the hub of the pulley under tension of the spring 43. The spring 43 and washer 41 also turn with the shaft and pulley so as to prevent wear on these parts when the machine is running. When the machine is stopped by sliding the sleeve 36 to withdraw the pulley from the clutch-member the friction between the yoke and the sleeve arrests the rotation of the latter and after the stopping of the shaft, the pulley is free to rotate without the sleeve as previously described.

For stopping the machine upon the breakage of a yarn or the exhaustion of the supply I provide means for automatically releasing the detent latch as now described: The outer rim of the frame 2 is formed with a circular flanged seat 75 on which is mounted a ring 76 which I term the brake-ring, see Fig. 1. This ring is adapted to be moved in the direction of rotation of the turret 8, as indicated by the arrow *d*, Figs. 2 and 6, by instrumentalities which act automatically upon the breakage or exhaustion of the yarn as later described. The movement of the ring 76 serves two purposes: first to disengage the detent latch to allow the operation of the clutch-controlling means; and second, to effect a braking action on the rotating turrets of the machine.

Secured to the ring 76 adjacent the clutch-controlling devices is a tripping element or block 77 formed with a beveled face 78 adapted to engage the beveled end 74 of the latch 59, see Fig. 2. When the ring 76 is moved in the direction indicated by the arrow *d* the beveled face 78 contacts with the bevel 74 to release the latch and to allow the lever 56 to be moved by the spring 65 to cause the disconnection of the driving devices. A link 79 connects the block 77 with the latch 59, see also Fig. 5, so that after the latch is released and the lever 56 moves

under impulse of the spring 65 the ring 76 will be turned still farther on its bearing to effect the braking action as later described. The link 79 also serves as a means for returning the ring to its initial position when the lever 56 is moved by the handle 53 to start the machine. It will be noted that where the link 79 engages the hole 80 in the block 77 there is sufficient play to allow the block to move into contact with the latch 59, to effect its release, without being restrained by the link.

The initial movement of the ring 76 to release the clutch devices is effected by means of arms 81 arranged at intervals around the machine, see Figs. 1 and 6, and operated by feeler-devices controlled by the delivering yarns from both sets of supplies. Preferably, the arms 81 are fulcrumed on studs 82 screwed into blocks 83 fastened to the flange 84 of the machine frame 2. The blocks 83 are secured to the flange 84 by means of screws 85 projecting through slots 86, and a spline 87 fits the peripheral groove 88 in the flange to keep the blocks from turning. On the brake-ring 76 are secured blocks 89, equal in number to the blocks 83, and fastened in the same manner by screws 90 passing through slots 91, and having splines 92 engaging the groove 93. The blocks 83 and 89 have coacting beveled faces 94 and 95 which act as wedges to lift the brake-ring 76 away from the flange 84 when the ring is turned in the direction indicated by the arrow *d*. The upper part of the brake-ring 76 is formed with an internal beveled face 96 adapted to engage a corresponding bevel 97 on the exterior of the turret 8, see Fig. 1. When the wedge-blocks 83 and 89 are caused to be engaged by the turning of the ring 76 they act to raise the latter to engage the ring with the turret as more fully described hereafter.

The arms 81 have slots 98 with which pins 99, driven into the ring 76, engage. It will be seen that by moving the arms in the direction indicated by the arrow *e*, Fig. 6, they will act to pry the ring to turn it in the same direction, as indicated by the arrow *d*, Figs. 2 and 6. The upper ends of the arms 81, which are preferably constructed of sheet metal, have fan-shaped heads 100 twisted at right angles to the body of the arms. Adapted to coact with these ends are feeler rods 101 and 102 arranged to slide in bearings in the brackets 10, see Fig. 1. The rod 101 is bent at right-angles at 103, see Fig. 1, and extends through a hole 104 in the rim of the turret 8, see Fig. 6. Its upper end is formed with a relatively long T-arm 125 105 bent back upon itself and curved downward at 106. Below the bend or elbow 103 is a collar 107, and between the collar and the bearing 108 is a coiled spring 110 which acts to normally lift the rod 101 to maintain its 130

lower end out of reach of the ends 100 of the arms 81.

Referring to Figs. 7 and 8, the upper yarn supply 11, represented by dot-and-dash lines, is supported on a spindle 111 held in a bearing in the deck of the carrier 9. The tube on which the yarn is wound fits a holder 112 which is adapted to rotate on the spindle 111 and carries at its lower end a ratchet-wheel 113. A rod 114 pivoted in bearings in an upright 120 carries a pawl 115 at its lower end adapted to engage the internal teeth of the ratchet-wheel 113 to control the rotation of the supply. At its upper end is an arm 116 having an eye through which the yarn y draws as it leads from the supply. A spring 117 connects one end of the pawl 115 to a wire arm 118 and tends to keep the pawl in engagement with its ratchet. The arm 118 is pivoted at the lower end of the spindle 111 with its outer end adapted to engage notches 119 in the under side of the carrier's deck. The arm 118 can be adjusted in these notches to vary the tension of the spring 117 so as to regulate the degree of tension of the yarn required to release the pawl from its ratchet to allow the turning of the supply. Supported in bearings in the upright 120 is a drop-wire 121 arranged to project down through the deck of the carrier 9. The drop-wire 121 has a crook 122 at its upper end, serving as a guiding eye for the yarn, and is weighted by a coil of wire 123 fastened around it near its lower end. The yarn y leads from the supply 11, under the crook 122, thence through the eye at the end of the arm 116 and back through the loop of the drop-wire, as shown in Fig. 8. From the drop-wire the yarn leads up to the braiding point z , see Fig. 1, and as the yarn is taken up by the braiding operation the tension on it will cause the arm 116 to be swung toward the drop-wire. This releases the pawl 115 from the ratchet-wheel 113 and allows the supply to rotate to deliver the yarn as required. The tension on the yarn y maintains the drop-wire in its raised position against a stop 124 on the upright 120, see Fig. 7, but when the yarn breaks or is exhausted the drop-wire will fall, under influence of gravity, to act on the feeler devices as later explained.

Referring to Figs. 1 and 9, the lower supplies 12 are mounted on holders 125 supported on the spindles 126 on the brackets 10, and have a similar arrangement of let-off mechanism. A rod 127 is pivoted in bearings in the standard 128 and carries a spring-arm 129 at its upper end provided with a guiding loop 130. At its lower end the rod 127 has an arm 131 connected by a spring 132 to the wire arm 133. The arm 133 is pivoted at the lower end of the spindle 126 and has a hooked end 134

engaging the notches 135. The arm 133 can be adjusted in the notches similarly to the arm 118 on the upper carrier 9, to adjust the tension of the spring 132. A second rod 136 is mounted in the standard 70 128 and carries a pawl 137 at its lower end adapted to engage the teeth on the ratchet-wheel 138. A coiled spring 145 on the rod 136, see Fig. 1, tends to maintain the pawl in engagement with the ratchet-wheel. At 75 its upper end the rod 136 carries a spring arm 139 adapted to be engaged by the arm 129 when the latter is moved under influence of the tension on the yarn x . When the yarn is taken up by the braiding action the 80 arm 129 swings against the arm 139 and the latter is moved to release the pawl 137 to allow the supply-holder to rotate and deliver the yarn. It will be observed that the arm 129 has a wide range of movement to adapt 85 it to render a sufficient length of yarn to allow it to pass either over or under the upper supplies without unwinding from the supply cop.

On the under side of the bracket 10 is the 90 feeler-rod 102 adapted to slide in the bearings 141 and 142. The rod 102 carries a coiled wire 143 which serves as a weight to keep the rod normally in position to prevent the engagement of its end with the arms 81. 95 The wire 143 contacts with the end of the bearing 142 to limit the movement of the rod in one direction and movement in the opposite direction is limited by a notch 144 in the hooked end 140 of the rod, see right-hand side of Fig. 1, which is adapted to engage the side of the bearing 141. When the tension on the yarn x is released, either by breakage of the yarn or exhaustion of the supply, the arm 129 will swing back 100 under influence of its spring 132 in the direction indicated by the arrow, Fig. 9. This carries the arm 131 against the hooked end 140 of the rod 102 to project the latter out 105 into position to engage the arm 81. 110

Having now described the whole arrangement of my machine in detail the method of operation of the stopping-mechanism and brake-device will next be explained. With the driving-pulley 23 in engagement with 115 its clutch-member 24 the driving-shaft is rotated to turn the outer turret 8 in the direction indicated by the arrow d , Figs. 2 and 6, and the inner turret 7 turns in the opposite direction. The lower yarn supplies 12 are carried around by the outer turret 8 and the upper supply carriers 9 are driven from the inner turret 7 and slide in the race-way 14. The yarns y lead from the supplies 11 under the loops 122 of the drop-wires 121 and up to the braiding point z and the yarn is delivered as required, as previously explained. When any one of the supplies 11 is exhausted or one of the yarns y breaks the drop-wire which is normally 120 125 130 135 140 145 150 155 160 165 170 175 180 185 190 195 200 205 210 215 220 225 230 suspended on the yarn will drop into position to contact with the feeler rod 101. As the turret 7 rotates in the direction opposite to that of the turret 8, which latter carries the feeler rods 101, the end of the drop-wire 121 will ride up over the downturned end 106 of the cross-arm 105 and act to depress the rod 101 against the action of its spring 110. The end of the rod 101 will therefore be thrown into position to contact with the head 100 of the arm 81. As the drop-wires 121 and feeler-rods 101 are moving in opposite directions, and since there is the same number of both around the circumference of the machine, it will be evident that a drop-wire will engage with a feeler-rod almost the instant it falls. The purpose of the relatively long cross-arm 105 is to provide that the drop-wire shall hold the feeler-rods 101 depressed during an interval long enough to insure that the rod engages one of the arms 81.

The lower yarns *a* lead from the supplies 12 through the guiding loops 130 and thence up to the braiding point *a*. When any one of these yarns breaks, or its supply is exhausted, the arm 129 which is normally controlled by the yarn will be released and the spring 132 will act through the arm 131 to project the feeler-rod 102 into position to engage one of the arms 81. The engagement of any one of the feeler-rods 101 and 102 with one of the arms 81 moves the latter in the direction indicated by the arrow *c*, Fig. 6, and this, in turn, moves the brake-ring 76 in the direction indicated by the arrow *d*. When the machine is running the ring 76 is in such position that there is a slight clearance between the bevel faces of the wedge-blocks 83 and 89 and the first movement of the ring under action of the arm 81 will not bring the wedge-blocks into operative contact. This is to prevent undue resistance to the rotation of the ring so that its first movement will be rapid and the relatively light feeler mechanism will not be subjected to severe strain. The first movement of the ring 76 under action of the feeler devices brings the bevel 78 of the block 77, see Fig. 2, against the beveled end 74 of the latch 59 and wedges the latter off of the detent pin 62. Immediately the latch is free the spring 65 acts to move the lever 56 to slide the yoke 45 and disengage the driving pulley 23 from the clutch-member 24, as previously described. This movement of the lever 56 also acts through the link 79 to carry the brake-ring 76 still farther in the direction indicated by the arrow *d* to bring the wedge-blocks 83 and 89 into engagement. The engagement of the bevel faces of the wedge-blocks causes the ring 76 to be lifted bodily on its bearing on the frame 2 to engage its beveled face 96 with the face 97 on the turret 8. This latter en-

gagement tends to force the whole turret upward against its bearing 143 on the head 16 of the turret 7 and as the two turrets are rotating in opposite directions the frictional resistance of their bearing surfaces will be multiplied. Add to this the fact that their contacting surfaces are being forced together to bind one against the other, and that the greater the pressure of the ring 76 against the turret, the stronger the tendency will be to rotate the ring and increase its upward pressure, and it will be seen that the braking force is cumulative, and therefore must give a maximum retarding effect to stop the machine. By this arrangement I take advantage of the momentum of the moving parts of the machine and convert it into a reacting force to arrest the operation of the machine after the clutch mechanism has been disengaged. In this way I am enabled to stop the machine almost instantaneously when a yarn breaks or a supply becomes exhausted and the broken end of the yarn is prevented from running into the fabric. This results in improving the quality of the braid, since the yarns can be pieced up without making imperfections or picking out ends and it also provides for more economical operation as the operator does not have to patch or repair the fabric. When the hand lever 53 is moved to throw the driving-pulley into engagement with its clutch-member the lever 56 acts through the link 79 to turn the brake-ring 76 back to release the wedge-blocks and the weight of the ring causes it to drop to free it from engagement with the turret 8.

By arranging the brake-ring to rotate with the turret to actuate the wedging devices, instead of providing a separate ring moved from the feeler devices, as in my previous invention, I not only simplify the structure of the machine, but I also take advantage of the momentum of the moving parts to react in a cumulative braking force as above described. In this feature my present invention shows improvement over the device of application, Serial No. 493,718, filed May 3rd, 1909.

It will be evident that modifications might be made in the structure and arrangement of my device without departing from the spirit and scope of the invention; therefore, without limiting myself to the exact form and arrangement shown, what I claim is:

1. In a braiding machine, the combination with two sets of yarn supplies, of turrets to revolve the sets of supplies in opposite directions, a central standard having bearings for the turrets, a brake-ring mounted on said standard and provided with wedge-blocks having beveled faces, oppositely beveled wedge-blocks mounted on the standard, and means to move the brake-ring rotatively to bring the respective

- wedge-blocks into engagement and raise the ring into contact with one of the turrets to apply a braking force.
2. In a braiding machine, the combination with two sets of yarn supplies, of turrets to revolve the sets of supplies in opposite directions, a central standard having bearings for the turrets, a brake-ring rotatably mounted on said standard and adapted to engage one of the turrets, means to rotate the brake-ring, and means operated by said ring in its rotation to move the brake-ring into engagement with said turret to apply a braking force.
3. In a braiding machine, the combination with two sets of yarn supplies, of turrets to revolve the sets of supplies in opposite directions, a brake-ring adapted to rotate in the direction of one of the turrets, means to rotate the brake-ring and means operated by said ring in its rotation to carry the brake-ring into engagement with said turret to apply a braking force.
4. In a braiding machine, the combination with two sets of yarn supplies, of turrets to revolve said supplies in opposite directions, a brake-ring adapted to rotate in the direction of one of the turrets, means to move the brake-ring rotatively from the turret and means actuated by said rotary movement to carry the brake-ring into contact with the turret to apply a braking force.
5. In a braiding machine, the combination with two sets of yarn supplies, of turrets to revolve said supplies in opposite directions, a brake-ring adapted to rotate in the direction of one of the turrets, means to move said ring rotatively, feeler devices on the turret to operate said means, and means brought into engagement by the rotary movement of the ring to carry the latter into engagement with the turret to apply a braking force.
6. In a braiding machine, the combination with two sets of yarn supplies, of turrets to revolve said supplies in opposite directions, a brake-ring adapted to rotate in the direction of one of the turrets, means to move said ring rotatively, feeler devices on the turret to operate said means, means controlled by the tension of the yarns delivering from the supplies to actuate the feeler devices, and means brought into engagement by the rotary movement of the brake-ring to carry the latter into engagement with the turret to apply a braking force.
7. In a braiding machine, the combination with two sets of yarn supplies, of turrets to revolve said supplies in opposite directions, a brake-ring adapted to rotate in the direction of one of the turrets, and wedges brought into engagement by the rotary movement of the brake-ring to carry the latter into engagement with the turret.
8. In a braiding machine, the combination with two sets of yarn supplies, of turrets rotating in opposite directions to revolve said supplies about a common axis and having adjacent bearing faces, a brake-ring adapted to rotate in the direction of one of the turrets, and means actuated by said ring in its rotation to carry it into engagement with one turret to force the latter against the other turret to effect a braking action.
9. In a braiding machine, the combination with two sets of yarn supplies, of turrets rotating in opposite directions to revolve said supplies about a common axis, a brake-ring adapted to rotate in the direction of one of the turrets, means to move said ring rotatively, and means to frictionally engage said ring with the turret, said means operating to bind one of the turrets against the other.
10. In a braiding machine, the combination with two sets of yarn supplies, of outer and inner turrets to revolve said sets of supplies in opposite directions, a stationary standard having bearings for said turrets, a bearing to limit the upward thrust of the inner turret, a rotative brake-ring mounted on the standard and adapted to engage the outer turret, and means brought into engagement by the rotative movement of the brake-ring to lift the brake-ring and raise the outer turret against the inner turret to force the latter against the thrust bearing to apply a braking force.
11. In a braiding machine, the combination with two sets of yarn supplies, of turrets to revolve said sets of supplies in opposite directions, a stationary standard having ball bearings on which the turrets rest, a bearing on the standard arranged to take the upward thrust of both turrets, a normally stationary brake-ring mounted on the turret to move rotatively, means to move the ring, and means brought into engagement by said rotative movement to force the ring against one of the turrets to raise said turret against the other turret and bind the latter against the thrust bearing.
12. In a braiding machine, the combination with two sets of yarn supplies, of turrets rotating in opposite directions to revolve said supplies about a common axis, one of said turrets formed with an annular beveled face, a rotatable brake-ring having an oppositely beveled annular face, and means brought into engagement by said ring when the latter is moved rotatively to bring into engagement the beveled faces on the ring and turret to force one turret against the other to apply a braking force.
13. In a braiding machine, the combination with a central, stationary standard, of turrets rotating in opposite directions on said standard, a tier of yarn supplies mounted on one of the turrets, a second tier of sup-

plies supported by said turret and revolved by the other turret, a brake-ring rotatably mounted on the standard, a plurality of arms adapted to move said brake-ring rotatively, feeler devices to engage said arms, means controlled by the yarns to operate the feeler devices, means actuated by the brake-ring in its first movement to cause the rotative movement of said ring to continue and means brought into engagement by said brake-ring during its rotative movement to force said ring into engagement with one of the turrets to apply a braking action.

14. In a braiding machine, the combination with two sets of yarn supplies, of turrets to revolve the sets of supplies in opposite directions, a normally stationary brake-ring adapted to rotate in the direction of one of the turrets, means to impart a rotary movement to the brake-ring, and means brought into engagement by said ring during its rotary movement to carry the ring against the turret to apply a braking force, said means acting to increase the braking tendency as the ring is moved rotatively through engagement with the turret.

15. In a braiding machine, the combination with two sets of yarn supplies, of outer and inner turrets to revolve the sets of supplies in opposite directions, a normally stationary brake-ring adapted to rotate in the direction of the outer turret, feeler devices controlled by the yarns from the supplies, means engaged by said feeler devices to initiate a rotary movement of the brake-ring, means to cause the rotary movement of said ring to continue, and means brought into engagement by said ring in its rotary movement to carry the ring into engagement with the outer turret to apply a braking force, said means acting to increase the braking tendency as the ring is moved through frictional engagement with the turret.

16. In a braiding machine, the combination with two sets of yarn supplies, of rotating turrets to revolve the sets of supplies in opposite directions, a driving shaft to rotate the turrets, driving means therefor, a clutch to connect the driving means with the shaft, means to shift the clutch to disconnect the driving means, a brake-ring rotatable in the direction of one of the turrets, means to rotate the ring, means to actuate the clutch-shifting means from said ring in its movement, and means to cause said ring to engage with one of the turrets to apply a braking force.

17. In a braiding machine, the combination with two sets of yarn supplies, of rotating turrets to revolve the sets of supplies in opposite directions, driving means to rotate the turrets, devices to disconnect the driving means, a brake-ring rotatable in the direction of one of the turrets to cause the operation of said disconnecting devices, means to

rotate said ring, and means brought into engagement by the rotary movement of the ring to carry the latter into engagement with one of the turrets to apply a braking force.

18. In a braiding machine, the combination with two sets of supplies, of rotating turrets to revolve said sets of supplies in opposite directions, driving means to rotate the turrets, means to connect and disconnect the driving means, detent means to maintain the driving means connected, a brake-ring adapted to rotate in the direction of one of the turrets, means operated by said ring in its movement to release the detent means, means to move the brake-ring, and means to bring the ring into engagement with one of the turrets to apply a braking force. 70

19. In a braiding machine, the combination with two sets of yarn supplies, of turrets to revolve said sets of supplies in opposite directions, means to drive the turrets, devices for controlling said driving means, a brake-ring adapted to engage one of the turrets, means controlled by the yarns to move the brake-ring, means actuated by the brake-ring in its movement to operate the controlling devices for the driving means, and means to carry the brake ring into engagement with the turret to apply a braking action after the operation of said controlling devices. 85

20. In a braiding machine, the combination with the rotating turret 8, of two tiers of supplies thereon oppositely revolved about the axis of the machine, a normally stationary brake-ring adapted to move rotatively in the direction of the turret 8, arms 81 to move the brake-ring, feelers 102 normally restrained from engagement with the arms 81, means controlled by the yarns from one set of supplies to project said feelers into the path of the arms 81, feelers 101 on the turret 8 normally restrained from engagement with the arms 81, drop-weights 121 controlled by the yarns from the other set of supplies and adapted to fall when released into position to engage the feelers and project said feelers into position to operate the arms 81, and means brought into engagement by the rotative movement of the brake-ring to force the latter against the turret 8 to apply a braking action. 100

21. In a braiding machine, the combination with rotating turrets, of a driving shaft to rotate the turrets, a driving pulley on said shaft, a clutch to connect the pulley with the shaft, a spring to carry the pulley into engagement with the clutch, a lever 56 to withdraw the pulley from the clutch, a spring 65 to operate said lever, detent means to hold the lever against action of the spring 65, a brake-ring adapted to move rotatively about the axis of the machine, yarn controlled feeler devices to initiate the rotative movement of the ring, means on said ring to re- 115 120 125 130

- lease the detent means, and means connecting the ring with the lever 56 to move the ring under influence of the spring 65 to apply a braking action after the driving pulley is disengaged from the clutch.
22. In a braiding machine, the combination with a driving shaft 19, of a clutch-member 24 fast on the shaft, a driving pulley 23 rotatable on the shaft and slidable thereon to engage the clutch-member, a sleeve 36 to slide the pulley, means to connect the sleeve with the pulley to allow the latter to rotate independently of the sleeve, a spring 43 to move the sleeve and slide the pulley into engagement with the clutch-member, a yoke 45 to slide the sleeve to withdraw the pulley from engagement with said clutch member, a lever to operate said yoke, a spring 65 of greater tension than the spring 43 to operate the lever, and detent means to hold the lever against the action of the spring 65 to maintain the yoke out of engagement with the sleeve 36 and allow the spring 43 to maintain the pulley 23 in engagement with the clutch member 24.
23. In a braiding machine, the combination with the driving shaft, of a clutch-member fast on the shaft, a driving element rotatable on the shaft and slidable thereon to engage the clutch-member, a sleeve 36 connected with the driving element, a spring to slide

the sleeve to bring the driving element into engagement with the clutch-member, a yoke 45 normally free of the sleeve 36 when the driving element is in engagement with said clutch-member, detent means to hold the yoke free of the sleeve, and means to move the yoke to engage the sleeve and withdraw the driving member from engagement when the detent means are released.

24. In a braiding machine, the combination with the driving shaft 19, of an overhanging bearing 22 therefor having a counterbore 40 at its outer end, a washer 41 in said counterbore, a sleeve 36 slidable within the counterbore and formed with a counterbore 42, a spring 43 in the counterbore 42 adapted to bear on the washer 41, a clutch-member 24 fast on the shaft 19, a driving-pulley 23 slidable on the shaft to engage the clutch-member, a flanged ring 38 connecting the hub of the pulley 23 with the sleeve 36, and a yoke 45 adapted to engage the sleeve to slide the pulley against the action of the spring 43.

In testimony whereof I affix my signature in presence of two witnesses.

SIMON W. WARDWELL.
